US00D885171S

(12) **United States Design Patent** (10) **Patent No.:** **US D885,171 S**
Koelling et al. (45) **Date of Patent:** **** May 26, 2020**

(54) **CHANNEL LOCK FASTENER**(71) Applicant: **Lockdowel, Inc.**, Fremont, CA (US)(72) Inventors: **Fred Koelling**, Foster City, CA (US);
Bryan Koelling, Carmel Valley, CA (US); **Daniel Savage**, San Mateo, CA (US); **Hoang Dang**, San Jose, CA (US)(73) Assignee: **Lockdowel, Inc.**, Fremont, CA (US)(***) Term: **15 Years**(21) Appl. No.: **29/698,855**(22) Filed: **Jul. 19, 2019****Related U.S. Application Data**

(63) Continuation of application No. 16/216,901, filed on Dec. 11, 2018, which is a continuation of application No. 15/215,506, filed on Jul. 20, 2016, now Pat. No. 10,197,081.

CLAIM

The ornamental design for a channel lock fastener, as shown and described.

DESCRIPTION

FIG. 1 is a perspective view of a channel lock fastener embodying our new design;

FIG. 2 is a front elevational view thereof, the rear elevational view being a mirror image thereof;

FIG. 3 is a right side elevational view thereof, the left side elevational view being a mirror image thereof;

FIG. 4 is a top plan view thereof; and,

FIG. 5 is a bottom plan view thereof.
